T. K. NORTH.
SUBMARINE MINE.
APPLICATION FILED MAR. 8, 1916.

1,280,526.

Patented Oct. 1, 1918.

UNITED STATES PATENT OFFICE.

THOMAS KEPPEL NORTH, OF WESTMINSTER, LONDON, ENGLAND, ASSIGNOR TO
VICKERS LIMITED, OF WESTMINSTER, ENGLAND.

SUBMARINE MINE.

1,280,526.

Specification of Letters Patent. Patented Oct. 1, 1918.

Application filed March 8, 1916. Serial No. 82,896.

To all whom it may concern:

Be it known that I, THOMAS KEPPEL NORTH, a subject of the King of Great Britain, residing at Vickers House, Broadway, 5 Westminster, in the county of London, England, have invented certain new and useful Improvements in or Relating to Submarine Mines, of which the following is a specification.

10 This invention relates to submarine mines of the kind comprising a flotation chamber constituting the mine proper, an anchor containing a drum on which is wound a cable connecting the anchor to the flotation chamber and a plummet or sounding ball connected by a line to a ratchet pawl adapted to engage with ratchet teeth on the cable drum of the anchor; this plummet holds the ratchet pawl out of engagement with the ratchet teeth during the descent of the anchor in 15 the water thereby enabling the cable drum to unwind, but when the plummet touches the sea bed the said pawl is caused to engage with the ratchet teeth and the anchor 20 then draws the flotation chamber beneath the surface of the water till it assumes a depth predetermined by the length of the line connecting the plummet to the ratchet pawl.

30 When a mine of this type is being raised during sweeping operations and the anchor and plummet are lifted off the sea bed, the aforesaid ratchet pawl may become disengaged from the ratchet teeth of the cable drum under the influence of the weight of 35 the plummet, with the result that the flotation chamber floats to the surface of the water, and enables the enemy to explode the mine by gun fire. A similar action occurs 40 in the event of the plummet dragging along the sea bed owing to the tide or to other causes.

The chief object of the present invention is to provide improved means for positively 45 preventing the pawl from becoming disengaged in the event of the weight of the plummet being again exerted upon it.

According to this invention the ratchet pawl (which may be under the influence of 50 a so-called "anti-vibration" device for preventing it from engaging with the ratchet teeth until the anchor has sunk to a predetermined depth even if the ratchet pawl is relieved of the weight of the plummet) is 55 provided with a movable device such as an

auxiliary pawl which is pivotally mounted thereon and is so constructed and arranged that when the ratchet pawl has moved into engagement with the ratchet teeth after the mine has been laid, the auxiliary pawl will 60 assume a position to engage with a fixed part so that the ratchet pawl cannot be disengaged from the ratchet teeth.

In order that the said invention may be clearly understood and readily carried into 65 effect we will describe the same more fully with reference to the accompanying drawing, in which:—

Figure 1 is a side elevation showing a constructional form of our improvements applied to a mine which is shown by chain lines, and

Fig. 2 is a view on a larger scale of the aforesaid ratchet and auxiliary pawls.

A is the flotation chamber, and A' is the 75 anchor. B is the ratchet pawl for engaging with the teeth of the usual ratchet wheel B' carried by the drum of the anchor cable, and b is the line connecting the ratchet pawl B to the plummet or sounding ball which is 80 not shown. C is the auxiliary pawl that prevents the ratchet pawl B from becoming disengaged from the teeth of the ratchet wheel B' after engagement has occurred.

The auxiliary pawl C is pivoted at c to 85 the ratchet pawl B and both these pawls are controlled by a helical spring c'. This auxiliary pawl together with the spring c' is normally housed within a cavity C' in the anchor casing. This is the position shown by 90 full lines in Figs. 1 and 2. When the ratchet pawl B engages with the ratchet wheel B', the spring c' will cause the auxiliary pawl C to assume the position shown by chain lines which position is such that 95 the lower end of the auxiliary pawl is situated close to the portion of the anchor casing contiguous to the cavity C'. If a pull should be exerted upon the plummet line b the ratchet pawl B will therefore not become disengaged from the ratchet wheel B'. 100

The aforesaid "anti-vibration" device as is well understood comprises a plunger D whose position varies with the number of revolutions that have been made by the anchor cable drum and which, until, a predetermined number of revolutions have taken place, lies in the path of a projection b' on the ratchet pawl B and prevents it 105 from engaging with the ratchet wheel B'. 110

In conjunction with the teeth on the ratchet wheel B' we employ a spring controlled arm E which is so shaped that by its coöperation with the said teeth it will act as a resilient brake during the rotation of the cable drum. This arm is pivoted on a bracket E' to which is also pivoted the ratchet pawl B. The ratchet wheel B' may be constituted by one of the flanges of the 10 cable drum.

What I claim and desire to secure by Letters Patent of the United States is:—

1. In a submarine mine, the combination with the drum for the anchor cable and the 15 member for engaging with teeth on said drum, of a movable device mounted on said member, for engaging with a fixed part when the member engages with the teeth.
2. In a submarine mine, the combination 20 with the drum for the anchor cable and the pawl for engaging with ratchet teeth on said drum, of a movable device, mounted on said pawl for engaging with a fixed part when the pawl engages with the ratchet teeth.
3. In a submarine mine, the combination 25 with the drum for the anchor cable, and the pawl for engaging with ratchet teeth on said drum of a device for engaging with a fixed part when the pawl engages with the ratchet teeth, and means for pivoting said device on the pawl.
4. In a submarine mine, the combination 35 with the drum for the anchor cable and the pawl for engaging with ratchet teeth on said drum, of a device for engaging with a fixed part when the pawl engages with the ratchet teeth, means for pivoting said device on the pawl, and a spring for controlling both the pawl and the said device.
5. In a submarine mine, the combination 40 with the drum for the anchor cable, and the pawl for engaging with ratchet teeth on said

drum, of an auxiliary pawl for engaging with a fixed part when the first mentioned pawl engages with the ratchet teeth, means 45 for pivoting said auxiliary pawl to the other pawl, and a spring for controlling both pawls.

6. In a submarine mine, the combination with the drum for the anchor cable, and the 50 pawl for engaging with ratchet teeth on said drum, of an auxiliary pawl normally housed within a cavity and engaging with a wall of said cavity when the first mentioned pawl engages with the ratchet teeth, means for 55 pivoting said auxiliary pawl to the other pawl, and a spring for controlling both pawls, this spring being housed within said cavity.

7. In a submarine mine, the combination 60 with the drum for the anchor cable and the member for engaging with teeth on said drum, of a movable device mounted on said member, for engaging with a fixed part when the member engages with the teeth 65 and a device preventing said member from engaging with the teeth until the cable drum has made a predetermined number of revolutions.

8. In a submarine mine, the combination 70 with the drum for the anchor cable, and the pawl for engaging with ratchet teeth on said drum, of a movable device mounted on said pawl, for engaging with a fixed part when the pawl engages with the ratchet teeth and 75 a device preventing said pawl from engaging with the ratchet teeth until the cable drum has made a predetermined number of revolutions.

In testimony whereof I affix my signature. 80
THOMAS KEPPEL NORTH.
